UNITED STATES PATENT OFFICE.

WILLIAM J. PATTERSON AND ALOYSIUS WICKLAND, OF PITTSBURG, PENNSYLVANIA, ASSIGNORS, BY MESNE ASSIGNMENTS, TO THE AMERICAN CASTING MACHINE CO., OF NEW JERSEY.

APPARATUS FOR DRYING AND COATING MOLDS.

SPECIFICATION forming part of Letters Patent No. 683,487, dated October 1, 1901.

Original application filed February 24, 1899, Serial No. 706,730. Divided and this application filed September 8, 1899. Serial No. 729,810. (No model.)

To all whom it may concern:

Be it known that we, WILLIAM J. PATTERSON and ALOYSIUS WICKLAND, residents of Pittsburgh, in the county of Allegheny and State of Pennsylvania, have invented a new and useful Improvement in Apparatus for Drying and Coating Molds; and we do hereby declare the following to be a full, clear, and exact description thereof.

10 Our invention relates to apparatus for drying and coating the interiors of molds in metal-casting apparatus, where a number of molds are mounted on a traveling carrier, the molds being poured at one end of the apparatus and discharged at the opposite end, such as set forth and described in Letters Patent of the United States No. 583,424, granted to A. M. Acklin May 25, 1897. In said Letters Patent there is set forth and claimed a method 15 of casting pig metal consisting in pouring the metal into molds partially submerged in water, passing said molds in a horizontal course through said water in the partially-submerged state, and then passing said molds 20 in a horizontal course through said water in a completely-submerged state. The molds are mounted on an endless carrier or chain, and after they have discharged their contents they pass down and return to point of pouring 25 in an inverted position. These molds after the pigs have been discharged are in a wetted condition, owing to their passage through the tank or the spraying of the molds after leaving the tank, and therefore when 30 formed of thin wrought metal the wrought iron or steel molds remain wet or damp in their course back to the receiving end of the machine to be again filled with pig metal, and if the highly-molten pig metal strikes the 35 molds when wet the metal is liable to sputter, wasting the same, while the metal may strike some of the workmen and burn them. The thin wrought-metal molds did not carry sufficient heat to dry the molds in their 40 return course. In such form of casting apparatus more or less trouble has been experienced by reason of the pigs adhering and sticking to the molds when solidified, and various attempts have been made to avoid 45 this difficulty, but with unsatisfactory results.

Devices for spraying the molds with water and mixtures of different refractory materials have been employed in various forms to insure the free delivery of the pigs from the molds, and coatings of lime, clay, or similar 55 refractory materials have been used for this purpose, and a mechanical device for imparting a blow to the molds or pigs just prior to their discharge has also been contrived. These methods of treatment are all more or 60 less objectionable, as they do not always work satisfactorily. The use of clay is particularly objectionable on pigs which are to be used in the basic open-hearth process or to be melted in a cupola prior to the Bessemer process, and 65 the use of lime is also to be avoided on pigs which are to be used in the acid process, all of which will be readily understood by those skilled in the art of making steel. Further than this, the use of washes made of lime, 70 clay, or other ordinary refractory materials has the effect of materially shortening the life of the molds, and is particularly severe in its action upon the bearing and wearing portions of an endless-carrier machine, as these mineral refractories have the effect of abrading 75 the working parts of the apparatus very rapidly.

We practically overcome the above objections by applying a fresh coating of carbonaceous material to the molds just prior to the introduction therein of the molten metal, and in addition to preserving the working faces of the molds from destruction by the molten metal and allowing the pigs to be readily discharged therefrom we find that this material is free from all of the above-stated objections, and from its nature, instead of abrading the working parts of the machine, it acts as a lubricator, thus preventing friction and loss of 80 power, and thereby preserves the working surfaces from destruction. This carbonaceous coating is also free from the objections heretofore stated with respect to the use of clay or lime on pigs which are to be used for 85 steel-making, as the carbonaceous matter is comparatively neutral and has no effect upon the lining of the furnaces or cupolas, nor does it affect the slag which is formed in the melting or refining process. It is found expedient 90 to 95 100

in such form of casting apparatus to have the molds formed with lips which overlap each other, so that when the metal is poured said overlapping lips will prevent the metal from falling in between the molds. The metal is liable to adhere to the molds, and especially if it drops on these lips it is liable to adhere thereto, so that this metal which has fallen on said lips will form a fin-like portion on the pig, which will be broken off when the pig is discharged into the receptacle at the discharge end of the apparatus, or if a portion still adheres it will be worn off or broken up in the handling of the pig afterward. This metal is wasted and is a matter of great loss.

In an application for patent filed by us February 24, 1899, Serial No. 706,730, of which this application is a division, a method is provided for drying the molds and coating them to prevent adherence of the metal to the bodies or overlapping lips, said method consisting, generally stated, in pouring the metal in a controllable stream into such endless connected series of traveling molds and moving the whole continuously at such speed that they will be uniformly filled and cooling the metal cast within the molds, preferably by water-cooling, and automatically delivering the pigs therefrom and then carrying the inverted molds over fuel-burning apparatus, so as to thoroughly dry the molds in their course back to the receiving end and prevent the flying of the metal above referred to, and at the same time to form a deposit of soot upon the faces of the molds as they return to be filled with the molten metal, the thin film of soot forming a surfacing which will prevent the metal from adhering to either the bodies or the lips of the molds. The present invention relates principally to certain improvements in the apparatus employed in practicing such method, which will be hereinafter more fully set forth and claimed.

To enable others skilled in the art to make and use our invention we will describe the same more fully, referring to the accompanying drawings, in which—

Figure 1 is a side elevation of a portion of a suitable casting apparatus to which our invention is applicable. Fig. 2 is a cross-section of same on line 2 2, Fig. 1. Fig. 3 is an enlarged view of a portion of the traveling mold-carrier. Fig. 4 is a cross-section of the tank.

Like letters of reference indicate like parts in each view.

While we have above referred to our invention as applicable to the method of casting pig-metal contained in said Patent No. 583,424, and will describe it in connection with said method in the present application, yet we do not wish to limit its application in any sense to the method of casting set forth in said patent.

In the drawings, Fig. 1 illustrates a portion of a suitable metal-casting apparatus, in which the letter *a* designates the frame or the

portion thereof adjacent to the pouring end of the apparatus. The tank *b* is supported by the frame *a*, and within said tank is the track *c*, upon which the wheels *d* of the endless chain *e* travel. The track *f* is the return-track supported by the frame *a*, and the wheels *d* travel on said track when the molds return in their inverted position to the pouring-point.

The endless chain or mold-carrier *e* may be of any suitable construction, and as it forms no part of our present invention a detailed description is not deemed necessary. The molds *g* are secured to the endless chain *e*, said molds having the overlapping-lips *g'*, which prevent the spilling of the metal in pouring between the molds and at the same time allow for the elongation of the endless chain, due to wear, without creating a gap between the molds. The chain *e* is mounted on suitable sprocket-wheels arranged at each end of the frame, the sprockets at the pouring end only being shown.

The tracks *h* may be used to carry the ladle 90 conveying the molten metal from the blast-furnace, while *i* represents the pouring-trough.

Beneath the frame *a* are the pits *k*, with tracks *m* arranged transversely of the frame *a*. Upon these tracks are the trucks *n*, supporting the fuel-burning apparatus, such as the pots or furnaces *o* of any suitable construction. These furnaces *o* are arranged at suitable intervals apart, and any number required for the purpose of our invention may be employed. The fire-chamber *o'* is provided with the grate-bars *o²*, and *o³* is the door for the admission of fuel. The furnaces *o*, when in the position shown in Fig. 2, are directly under the frame *a*, and the molds *g* in their inverted position travel directly over said furnaces, so as to be heated and dried thereby and receive the coating of soot from the smoke rising from the furnaces. In order to direct the products of combustion into the molds, the conical hood *p* is provided.

Any suitable furnaces or burners may be used, and we do not wish to limit ourselves in any manner to the particular form of apparatus for burning the fuel beneath the molds. Where the furnace is such as illustrated and employs solid fuel, when the apparatus is not in operation the furnace may be run to one side of the frame on the tracks *m*, so that undue heating of the molds when at a standstill is avoided.

In the use of the apparatus the metal is poured into the molds as they pass under the pouring-ladle. The molds are then cooled—such as by being carried through the cooling liquid of the tank (not shown)—and when they arrive at the opposite end of the frame the pigs are discharged from said molds. The molds then return in an inverted position, as shown in Fig. 1. The molds which have previously passed through the water of the tank or been wet in other ways in connection with the cooling of the metal therein are thor-

oughly dried as they pass over the tops of the furnaces *o*, the heat from the same being directed into the inverted molds and quickly drying them, so that all liability of the metal being poured into wet molds is overcome. For the purpose of smoking the molds any suitable smoke-producing fuel can be used which will form a sooty greasy coating on the surface of the molds, and the fact that the molds are comparatively moist or damp when brought above the furnaces causes the soot to more easily deposit thereon and to adhere more firmly to the lips and interiors of the molds. For this purpose bituminous coal may be employed and only enough air admitted to the furnaces to support a slow combustion, from which a heavy smoke discharge is obtained. Where oil or other gaseous or liquid fuel is used, the conditions are such as to cause imperfect combustion, generating smoke, while obtaining sufficient heat for the drying of the molds. Any carbonaceous fuel which, when imperfectly consumed, will deposit the soot on the molds may, of course, be employed.

In pouring the metal, as stated above, it is liable to drop on the overlapping lips *g'* and adhere thereto, so that when the molds arrive at the point of discharge this thin portion is broken off by the fall of the pigs into the receptacle placed there to receive them or in the later handling of the pigs and is lost. The coating of the molds with soot, as above set forth, forms a smooth or greasy surface both in the interiors or bodies of the molds and upon these lips, and the metal, instead of adhering to the lips, slips back into the molds, so that no fins are formed. The coating further acts to protect the molds when the metal is poured.

What we claim as our invention, and desire to secure by Letters Patent, is—

1. In a metal-casting apparatus, the combination with a suitable frame, of an endless connected series of traveling metal-molds, means for filling said molds successively, means for subjecting the molds and their contents to the action of water for cooling such contents, and drying apparatus located beneath the said molds in their return course to the receiving end of the apparatus, whereby the empty molds are successively dried in passing to their receiving position.

2. In a metal-casting apparatus, the combination with a suitable frame, of an endless connected series of traveling metal-molds, means for filling the molds, means for sub-

jecting the molds and their contents to water for cooling such contents, and smoke-discharging apparatus located beneath said molds in their return path to the receiving end of the apparatus and adapted to dry the molds and to deposit a coating of soot thereon, substantially as described.

3. In metal-casting apparatus, the combination with a suitable frame, of an endless connected series of traveling metal-molds, said molds having overlapping lips, means for filling the molds, means for subjecting the molds and their contents to water for cooling such contents, and smoke-discharging apparatus located beneath said molds in their return course to the receiving end of the apparatus and adapted to dry the molds and to deposit a coating of soot on the lips of said molds, substantially as set forth.

4. In metal-casting apparatus, the combination with a suitable frame, of an endless connected series of traveling metal-molds passing around the same, and fuel-burning apparatus beneath said molds in their return course to the receiving end of the apparatus, and having a flue extending up to said molds, said molds in their inverted position acting to substantially close said flue, substantially as set forth.

5. In metal-casting apparatus, the combination with a suitable frame, of an endless connected series of traveling metal-molds passing around the same, a tank containing liquid through which said molds pass when containing the metal, and fuel-burning apparatus beneath said molds in their return course to the receiving end of the apparatus, and having a flue extending up to said molds, said molds in their inverted position acting to substantially close said flue, substantially as set forth.

6. The combination with one or more molds, of a furnace located beneath the same and suitable deflectors to direct the products of combustion into the molds aforesaid whereby the carbonaceous products of said furnace are disposed against the interior walls of said molds.

In testimony whereof we, the said WILLIAM J. PATTERSON and ALOYSIUS WICKLAND, have hereunto set our hands.

WILLIAM J. PATTERSON.
ALOYSIUS WICKLAND.
